**SPEED INCREASER ATTACHMENT
FOR FOOD MACHINES**

Richard S. Hartley, Troy, Ohio, assignor to The Hobart Manufacturing Company, Troy, Ohio

Filed May 25, 1970, Ser. No. 23,111

Term of patent 14 years

Int. Cl. D15—08

U.S. Cl. D55—1

FIG. 1 is a side view of my new design for a speed increaser attachment for food machines;

FIG. 2 is a side view of the side opposite from FIG. 1;

FIG. 3 is a view from the top of FIG. 1;

FIG. 4 is a view from the bottom of FIG. 2;

FIG. 5 is an end view, as seen from the left of FIG. 1; and

FIG. 6 is an end view as seen from the left of FIG. 2.

I claim:

The ornamental design for a speed increaser attachment for food machines, substantially as shown and described.
